BORING BAR

Fritz Walther, Plauen i. V., Germany

Application July 31, 1935, Serial No. 34,086
In Germany August 11, 1934

4 Claims. (Cl. 77—56)

This invention relates to a boring bar.

In known boring bars disposed between centers and intended for fine work the portion carrying the tool can be moved by its own weight at a certain position of the tool edge, after elimination of the centering action affecting it, so as to bring the edge out of contact with the bored surface. If, however, the edge is not in highest position, it cannot be retracted from the bored surface but is pressed thereon by the weight of the boring bar which cannot be removed without injuring the bored surface or the edge itself.

It has been proposed to overcome these drawbacks by providing the two portions of the boring bar for mutual centering with cooperating annular guides and making use of a tension member which will rigidly connect both portions and if released permit the tool carrying portion to swing out. This construction is, however, open to the objection that prior to the withdrawal of the bar from the bore the tension member connecting both portions has to be released to permit the bar to be swung back by the action of a spring.

The invention eliminates these defects of the known types of boring bars and makes possible automatic and positive retraction of the tool edge from the bored surface at any position of the edge, by providing in a central longitudinal bore of the bar a slide member subjected to the action of a spring to abut against the center point of the driver, which member by means of a cone or an inclined surface and the radial displacement of a thrust pin causes the tool to be lifted off from the working surface at any position of the edge.

One form of the invention is illustrated by way of example only in the accompanying drawing, in which a boring bar according to the invention is shown, partly in longitudinal section.

In the drawing:—

Figure 1 shows an elevation partly in section of a boring bar and associated parts embodying the invention;

Fig. 2 is a cross section taken on line II—II of Fig. 1, on a larger scale; and

Fig. 3 is a cross section taken on line III—III of Fig. 1, also on a larger scale.

Referring to the drawing, 1 is a non-pivotal part of the boring bar and 2 the pivotable part thereof which at its ends is arranged between the centers 3 and 4. The center 3 has a flattened conical end which extends into a bore 5 of the part 2 and engages a slide member 6, longitudinally displaceable in the bore 5 against the action of a compression spring 8. The center 3 also

engages a conical seating 19 on the mouth of the bore in the boring bar 2, to center said end during operation.

The slide member 6 has an inclined surface 7 cooperating in a manner described hereinafter with a thrust pin 12 fixed in the pivotable part 2 near its end. The part 2 is pivoted in the part 1 by means of a universal joint comprising pivot pins 13, 15 and an elastic ring 14, the part 2 being jointed to the ring 14 by the pivot pin 13, and the ring 14 jointed to the part 1 by the pivot pin 15. The pivot pin 15 traverses a bore in the ring 14 which is large enough to permit limited axial movement of the part 1 relatively to the non-pivoting part 1.

If after completion of the boring operation carried out by the tools 9 and 10 the boring bar 1, 2 is withdrawn from the centering abutment 11, the spring 8 will cause displacement of the slide member 6 relatively to the part 2 and the thrust pin 12 will co-operate with the inclined surface 7 to lower the left hand end of the part 2. Consequently, the part 2 will be swung about the shaft 13 of the joint 14, 15 connecting the driving part 1 with the pivotable part 2, this movement being possible owing to the flattened point of the conical end sliding on the flat end of the member 6 in such a way that the tools 9 and 10 will be retracted from the working surfaces and the boring bar 1, 2 can be withdrawn from the bore without being damaged. The elasticity of the ring also prevents transmission of vibration from the drive to the tool.

In the construction shown the attachment of the boring bar to the spindle of the drilling machine is particularly simplified by providing a sleeve 16 carrying the center 3, with a Morse taper on its outer face 17. To obtain vibrationless driving of the spindle it is advisable to arrange the center 3 within the bearing 18 of the drive.

The operation of the present invention is as follows:

The center point of the member 3 is somewhat flattened and merely engages or abuts the end surface of the slide 6 in such a manner that this end can move transversely to the center 3. Upon withdrawing the center support 11, the tool bar 2, under the action of the spring 8, and utilizing the axial plan of the universal joint 14, 15, is forced to the right carrying with it the thrust pin 12, while the slide 6 remains held by the spring 8 against the flat point of the center 3. The conical seat 19 at left-hand end of the tool bar 2 thus separates from the center 3 and the

movement of the thrust pin 12, which is mounted with play in the wall of the bore 5 and of which the outer end bears against the inner surface of the bushing 16, causes the slide member and with it the left-hand end of the tool bar to move upwardly.

From the foregoing, the importance of the universal joint 14, 15 is evident. This joint allows the tilting movement of the tool bar 2, by means of the pressure on the thrust pin 12 and the spring 8, to withdraw the cutters from the work. The tool bar obviously can move only in one direction which is imposed upon it by the movement of the thrust pin 12 against the slide 6. Another purpose of the universal joint is to transmit the drive of the driving member 1 to the tool bar 2 without vibration and bending action. Obviously the universal joint supports the tool bar after withdrawing of the support 11, and the tool bar tilts about the axis 13. The universal joint therefore cannot be omitted as otherwise the tool bar would not be driven by the driving member 1, nor could it tilt about the pin 13.

I claim:—

1. A boring bar for operation between two centers comprising a driving member, a tool carrying member having an axial bore at one end in which one of the centers engages a slide member in said bore, said slide member having an inclined side face and abutting at one end 25 against a flattened point of said center, a spring operative between the slide member and the tool carrying member, joint means connecting the tool carrying member with the driving member and enabling the tool carrying member to pivot 30 in the driving member in any direction transverse to their common axis, said joint means providing for limited axial movement between said driving and tool carrying members, and a thrust pin in the wall of said bore and cooperating 35 with the inclined surface of the slide member to pivot the tool carrying member about the joint as a result of said limited axial movement.
2. A boring bar for operation between two centers, comprising a driving part, a tool-carrying part, means jointedly connecting said parts including a pivot pin about which the tool-carrying part can swing transversely to its axis, a slide member longitudinally displaceable in an axial bore in one end of the tool-carrying part 40 and slidably abutting at one end against one of the centers which extends into said bore, said slide member having an inclined face, a compression spring operating between the tool-carrying part and the other end of said slide member, said spring being coaxial with said tool-carrying part, and a thrust pin cooperating with the 45 inclined face of said slide member and adapted to be radially moved by axial displacement of the said slide member by said spring on retraction of the other center from the boring bar, the joint means being adapted to allow a limited 50 axial movement of the tool-carrying part relatively to the driving part, and comprising a universal joint having one of its parts of elastic material.

ber, said spring being coaxial with said tool-carrying part, and a thrust pin cooperating with the inclined face of said slide member and adapted to be radially moved by axial displacement of the said slide member by said spring on retraction of the other center from the boring bar, the joint means being adapted to allow a limited axial movement of the tool-carrying part relatively to the driving part.

3. A boring bar for operation between two centers comprising a driving member, a tool carrying member having an axial bore at one end in which one of the centers engages a slide member in said bore, said slide member having an inclined side face and abutting at one end 15 against a flattened point of said center, a spring operative between the slide member and the tool carrying member, joint means connecting the tool carrying member with the driving member and enabling the tool carrying member to pivot 20 in the driving member in any direction transverse to their common axis, said joint means providing for limited axial movement between said driving and tool carrying members, and a thrust pin in the wall of said bore and cooperating 25 with the inclined surface of the slide member to pivot the tool carrying member about the joint as a result of said limited axial movement, said joint means comprising a universal joint having one of its parts of elastic material.

4. A boring bar for operation between two centers, comprising a driving part, a tool-carrying part, means jointedly connecting said parts including a pivot pin about which the tool-carrying part can swing transversely to its axis, a slide member longitudinally displaceable in an axial bore in one end of the tool-carrying part and slidably abutting at one end against one of the centers which extends into said bore, said slide member having an inclined face, a compression spring operating between the tool-carrying part and the other end of said slide member, said spring being coaxial with said tool-carrying part, and a thrust pin cooperating with the 40 inclined face of said slide member and adapted to be radially moved by axial displacement of the said slide member by said spring on retraction of the other center from the boring bar, the joint means being adapted to allow a limited 45 axial movement of the tool-carrying part relatively to the driving part, and comprising a universal joint having one of its parts of elastic material.
